CARTRIDGE LOADING MOTION PICTURE PROJECTOR

Martin S. Ackerman, East Hills, and George Hardy, Huntingdon, N.Y., assignors to Perfect Film & Chemical Corporation, Manhasset, N.Y., a corporation of New York

Filed Aug. 27, 1968, Ser. No. 13,288

Term of patent 14 years

Int. Cl. D16—04

U.S. Cl. D61—1

FIG. 1

FIG. 2

FIG. 3

FIG. 5

FIG. 4

FIG. 1 is a front elevational view of a cartridge loading motion picture projector showing our new design;

FIG. 2 is a right side elevational view thereof;

FIG. 3 is a left side elevational view thereof;

FIG. 4 is a top plan view thereof; and,

FIG. 5 is a rear elevational view thereof in reduced scale.

The bottom of the cartridge loading motion picture projector is plain.

We claim:

The ornamental design for a cartridge loading motion picture projector, as shown and described.
